INVENTOR

ATTORNEY

UNITED STATES PATENT OFFICE

CARL W. HOLLINGSWORTH, OF MARSHALLTOWN, IOWA, ASSIGNOR, BY MESNE ASSIGNMENTS, TO OLE G. HERM, OF MARSHALLTOWN, IOWA

CLUTCH MECHANISM

Application filed December 27, 1927. Serial No. 242,705.

This invention relates to certain novel improvements in clutch mechanisms and is particularly directed to a device particularly adapted for use in connection with awnings or the like.

The salient object of my invention is to provide a simple and inexpensive device which will be arranged to engage a projecting portion on a movable member so as to stop said movable member in any desired number of predetermined points.

Another object of the invention is to arrange a device of the foregoing character in such a manner that it may be expeditiously released when so desired.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is an elevational view depicting a preferred embodiment of my invention associated with an awning;

Fig. 2 is a sectional detail view taken substantially on the line 2—2 on Fig. 1;

Fig. 3 is an elevational view depicting a preferred embodiment of my invention and in which certain parts are broken away;

Fig. 4 is a detail view taken on the line 4—4 on Fig. 3; and

Fig. 5 is a detail view taken on the line 5—5 on Fig. 3.

In the drawings, where I have illustrated a preferred embodiment of my invention, I disclose said invention in connection with an awning of the type employed on automotive vehicles. The embodiment of the invention illustrated includes brackets 10 and 11 which are adapted to be suitably secured to the body of the vehicle with which the awning is associated. The upper portions of the brackets 10 and 11 are inwardly disposed as indicated at 12 and 13 and are adapted to suitably support a curtain roller 14 which includes a spring construction therein adapted to urge said roller in a predetermined direction and this construction is known in the

art as a self winding roller. Mounted for winding upon the roller 14 is a sheet of material such as canvas which is adapted to provide the body portion of the awning. The lower portions of the brackets 10 and 11 are outwardly disposed as indicated at 16 and 17 and a substantially U-shaped member 18 is pivotally mounted in suitable openings provided in the portions 16 and 17. One end portion of the sheet of material 15 is looped about the bight portion 19 of the member 18. Therefore when said member 18 is pivoted about its support, said sheet of material 15 is withdrawn from the roller 14 in the manner illustrated in dotted lines in Fig. 2 so as to afford protection against the sun or inclement weather.

In order to hold the member 18 and therefore the sheet of material 15 in various positions, I provide a clutch member which includes a substantially circular cup 20. The bottom 21 of the cup 20 is offset at substantially the mid portion thereof as indicated at 22 so as to provide a passage through which the portion 16 may extend so as to slidably associate the cup 20 with said portion 16. A slot 23 is provided in the bottom 21 through which the portion 24 of the member 18 extends. As best illustrated in Fig. 4 the portion 24 is substantially U-shaped and includes a projection 25 which is disposed interiorly of the cup 20, the bight portion of said portion 24 extending through an opening 26 in the portion 16 and the slot 23, it being apparent that said slot 23 is provided in the offset portion 22. As illustrated best in Fig. 3 at spaced apart intervals on the rim of the cup 20, lugs 27 are struck inwardly. In Fig. 3, three lugs 27 are disclosed but it is to be understood that any number might be provided dependent upon the number of positions in which it was desired to stop the member 18.

Under normal conditions the member 18 and the sheet of material 15 are disposed in the position best illustrated by the full lines in Fig. 2. In order to bring the sheet of material into operative position the member 18 is moved outwardly or inwardly in the manner depicted by the dotted lines in this figure, which retracts the sheet of material

from the roller 14 against the action of the spring therein. As the member 18 is moved outwardly, the projection 25 passes over the lugs 27, the end of the member 25 being tapered as indicated at 28, so as to facilitate this passage. When the member 18 has attained the desired position the user permits the arm 18 and therefore the projection 25 to move in the direction of the action of the 10 spring in the roller 14 and the projection 25 engages the nearest lug 27 and this holds the arm 18 against further movement. When it is desired to release the projection 25 from the lug 27, the user grips the cup 20 and slides 15 it upwardly along the portion 16 until the lug 27 is dis-engaged from the projection 25 and thus the spring in the roller 14 retracts the arm 18 into the full line position of Fig. 2.

20 It is apparent from the foregoing description that I have provided a very simple and inexpensive clutching device which is arranged such that the arm 18 may be stopped in any desired number of positions and I 25 have also arranged the device in such a manner that the stopping means may be quickly and expeditiously released.

While I have illustrated and described the preferred form of construction for carrying 30 my invention into effect, this is capable of variation and modification, without departing from the spirit of the invention. I, therefore, do not wish to be limited to the precise details of construction set forth, but 35 desire to avail myself of such variations and modifications as come within the scope of the appended claims.

Having thus described my invention what 40 I claim as new and desire to protect by Letters Patent is:

1. In a device of the class described, a bracket, an arm pivotally mounted on said bracket, a projection on said arm, a member slidably mounted on said bracket, lugs 45 formed on said member at spaced intervals, means for urging said arm in a predetermined direction, said projection selectively engaging said lugs to limit movement of said arm.

50 2. In a device of the class described, a bracket, a cup, a portion offset from the bottom of said cup providing a passage to slidably receive said bracket, an arm pivotally mounted on said bracket having a 55 projection disposed within said cup, means for urging said arm in a given direction, lugs formed on the rim of said cup and disposed interiorly thereof adapted to selectively engage said projection whereby to limit movement of said arm in said given direction.

60 3. In a device of the class described, a bracket, a cup, a portion offset from the bottom of said cup providing a passage, to slidably receive said bracket, an arm pivotally mounted on said bracket having a pro-

jection disposed within said cup, means for urging said arm in a given direction, lugs formed on the rim of said cup and disposed interiorly thereof adapted to selectively engage said projection whereby to limit movement of said arm in said given direction, said offset portion having a slot formed therein through which said arm projects whereby said cup may be slid along said member to disengage said projection from said lugs. 70

4. In a device of the class described, a bracket, an arm pivotally mounted on said bracket, a projection on said arm, a member slidably mounted relative to said projection and said bracket, spaced lugs formed on said 80 slidably member, means for urging said arm in a predetermined direction, said member being slidably mounted whereby said projection may be selectively brought into engagement with said lugs to limit the movement of said arm in various positions of its movement.

In testimony whereof I affix my signature.

CARL W. HOLLINGSWORTH.
